UNITED STATES PATENT OFFICE

ALLEN W. MORTON, OF BALTIMORE, MARYLAND, ASSIGNOR TO THE AMERICAN HAMMERED PISTON RING COMPANY, OF BALTIMORE, MARYLAND, A CORPORATION OF MARYLAND

PISTON RING

Application filed June 3, 1932. Serial No. 615,218.

My invention relates to piston rings, and particularly to rings containing radial slots or openings employed to facilitate oil drainage as well as to control the circulation of 5 the oil about the ring.

This application constitutes an improvement on my co-pending application, Ser. No. 530,963, filed April 17, 1931, Patent No. 1,862,059, granted June 7, 1932.

10 My improvement consists of a one-piece split ring containing series of spaced radial slots or openings, and series of aligning arcuate grooves in the outer face of the ring in registry with certain of the slots.

15 An object of my invention is to produce a slotted oil ring containing series of radially disposed slots, all of said slots lying in a common plane located centrally of the side faces of the ring, and certain of which in 20 each series are connected in such manner as to insure proper lubrication when such rings are installed in badly worn cylinders.

Another object of my invention is to construct a ring of this character so as to avoid 25 the formation of corners or pockets which will arrest the flow of oil and bring about the formation of carbon.

Still another object of the invention is to so form the parts of the ring as to facilitate 30 rapid and practically unrestricted transfer of oil from the outside to the inside of the ring, as well as to localize and control oil circulation about the ring.

Other objects will appear from the following description, when read in connection 35 with the accompanying drawing, in which:—

Fig. 1 is a view in elevation, with parts broken away, of one form of slotted ring embodying my invention;

40 Fig. 2 is a section on line II—II of Fig. 1, showing the relation of the ring to the cylinder wall after the ring becomes worn, the showing being somewhat exaggerated;

Fig. 3 is a central horizontal section of 45 the ring shown in Fig. 1, the ring joint being open;

Fig. 4 is a top plan view of a piston showing the position of the rings in a worn cylinder; and

50 Fig. 5 is a central horizontal section

through a modified form of ring, in which the solid portions between adjacent slots are of rounded contour.

Referring first to Figs. 1 to 4 of the drawings, the reference character 6 designates a one-piece split ring or annulus containing a conventional joint 7. As shown, the ring contains aligned outwardly flaring radial slots 8 opening on the inner face of the ring, all of which slots lie in a common plane located centrally of the side faces of the ring.

Adjacent slots are connected by cutting away the outer surface of the ring, as at 12. The bottoms of these cuts or grooves 12 are spaced from the outer face of the ring, as shown in Figs. 2 and 3. These cuts cooperate with the openings or slots which they connect, to form and define two independent co-planar series of interconnected openings or slots of substantially 180° in extent, and 70 diametrically related.

These series are separated at points 13 and 14 by solid portions of the ring which extend intact and imperforate from the inner to the outer face of the ring or annulus, so that when the ring is in place in the cylinder and the ring joint is closed, oil circulation is provided throughout an extent of approximately 180° of the ring circumference on either side of said solid portions. These solid portions 13 and 14 of the ring are preferably displaced approximately 90° from a diametral plane passing through the ring joint, the plane coinciding substantially with the line designated A in Fig. 3.

The cuts 12 joining adjacent slots and cooperating with them are preferably of the same width as the slots, so as to provide ample oil circulation grooves or ducts, and to make the sides of the slots continuous and uninterrupted between the inner and outer faces of the ring. These slots and grooves are of substantial width, but form side lands 9 and 11 of sufficient section not to unduly weaken the ring.

I find that material advantage results from forming the oil drainage slots and peripheral grooves or connecting ducts of the same width,—the sides of the slots being in the

same planes with the sides of the grooves, as clearly shown in Fig. 2 of the drawing. By such a construction, the path for the flow of oil scraped off the cylinder by the oil scraping edges of the ring is unrestricted and the ring is properly ventilated, even in high speed, high compression engines of the most recent type.

- This construction will be more evident
- 10 from an examination of Fig. 2 of the drawing, wherein the line 15 designates the plane of one of the side walls of the slots 8, and this plane is also the plane of the peripheral connecting groove or duct wall defined by
- 15 the inner surface of the ring land 9. In similar manner, reference character 16 designates the continuous uninterrupted surface formed by the other wall of the slots and the inner face of ring land 11.
- 20 It is almost universal practice to manufacture piston rings so that they have a "plus circularity". This means that the ring diameter A (see Fig. 3) is greater than the ring diameter B when the ring with its joint closed
- 25 is placed in a flexible band. This gives the ring greater tension on the diameter A than on the diameter B, and compensates for the weakening of the ring at the point where the joint is cut. By careful design, the amount
- 30 of "plus circularity" can be so chosen as to give the ring satisfactory tension throughout its circumference. In use, the face of the ring adjacent the joint and also diametrically across from the joint will wear away
- 35 faster than the face of the ring at the ends of diameter B, because of the greater tension exerted along diameter A. This will result eventually in such wear that the diameter B becomes greater than the diameter A.
- 40 It is well known that engine cylinders become worn to elliptical form by the rocking of the piston or the side thrust of the piston because of the angularity of the connecting rod with respect to the axis of the piston.
- 45 Consequently, in engines having badly worn cylinders the rings naturally assume such a position that their longer diameters coincide with the longer diameter of the worn cylinders. This means that in engines having
- 50 badly worn cylinders the rings, after some degree of wear, generally take up a position with the diameter A approximately parallel to the axis of the wrist pin. By examining a great number of engines having worn cylinders, I have discovered that in the majority of cases the ring joints will be found to lie within an arc of approximately 45° one side or the other of the wrist pin axis.

This will be more clear from an examination of Fig. 4 of the drawing, wherein 18 designates the top of a piston having wrist pin bearings 19 containing a wrist pin 20. This piston is shown as containing the usual three piston rings, the joints of which are

65 designated 21, 22 and 23. The axis of the

wrist pin is designated 24. It will be found in the majority of cases that piston rings in worn cylinders will assume a position where their joints lie somewhere within the arc of angle θ , either one side or the other of the wrist pin axis. This means that the rings have been worn to "minus circularity", i. e., that diameter B is greater than diameter A, and that the rings have shifted so that diameter B is approximately at right angles to this axis 24. It is well known that because of the rotation of an engine constantly in the same direction, oil tends to accumulate on one side of the piston or the cylinder, and in worn cylinders this accumulation occurs on one side or the other of the wrist pin axis.

Accordingly, it is my purpose to provide at least two series of peripherally connected slots in a ring and to separate the two series at points 13 and 14, so that when such rings are used in worn cylinders and the rings also become worn in, oil will be distributed throughout the area between the lines 25 and 26 at the ends of axis 24 and will also be drained therefrom. The slots and short peripheral connecting grooves in each series provide arcuate outwardly open ducts through which the oil can flow without retardation and be distributed more or less evenly over the face of the cylinder throughout its entire circumference without any possibility of portions of the cylinder running dry.

In a piston ring containing a continuous groove, oil has a tendency to work around the ring always in the same direction, due to the particular shape of the cylinder caused by wear, i. e. either clockwise or counterclockwise. Consequently, one portion of the cylinder may not receive sufficient oil since with a continuous groove with openings extending inwardly therefrom, the oil may pass to the rear of the ring before it is properly distributed. By forming two separate series of oil circulation and drainage aperturing, however, the tendency of the oil to circulate in one direction is lessened, and since the joints generally assume such positions that diametral planes passing through them are substantially in line with the wrist pin axis, the oil on the oily side of the piston or the cylinder is made to circulate in both directions, producing more uniform distribution.

Although the ring shown in Fig. 3 operates satisfactorily, I find that the retardation of oil can be lessened and the formation of pockets in which oil can collect substantially eliminated, by the structure shown in Fig. 5.

Referring now to this figure, the reference character 27 designates a one-piece split ring of the same character as that shown in Fig. 1. This ring contains radial slots 28, adjacent slots being connected by cuts or ducts 29, similar to those described with reference to

Fig. 1. Likewise, these slots 28 are of the same width as the ducts 29, and cooperate with them to form two independent coplanar series of interconnected openings or slots, 5 each series extending approximately 180° around the ring and separated by imperforate portions of the ring or annulus 31 and 32, which form solid walls that extend across the face of the annulus and are intact from 10 its inner face entirely to its peripheral face, in a manner similar to solid portions 13 and 14 of the ring shown in Fig. 1.

The ring shown in Fig. 5, in which the outer faces 34 of the portions 33 forming 15 the end walls of adjacent slots are of smooth rounded contour, provides a construction whereby any possible restriction in the connecting passages of adjacent slots is reduced to a minimum, and eddying of the oil is substantially wholly eliminated.

By reference to Fig. 5, it will be noted that the outer rounded faces 34 merge into the diverging portions 35 and 36 without abrupt transition. Consequently, when oil circulates 25 around the ring through the ducts 29 from one slot to another, it encounters no sharp edges or corners to impede its movement, hence all tendencies to eddy or "bubble" are substantially eliminated. In this figure, 30 I have shown the ring as provided with solid imperforate portions separating each series of slots, but it will be obvious that the advantages of the rounded connecting portions between adjacent slots will still be present if 35 the solid portions are omitted. Accordingly, I wish it to be understood that rings embodying the rounded surfaces, as described, will function to prevent eddying of the oil regardless of the presence or absence of the solid 40 portions. I, therefore, desire to claim generically rings having this rounded contour, and in which these solid portions may or may not be present.

The type of ring shown in Fig. 5 not only 45 results in improved operation, but it can be more easily manufactured. According to the principles of hydraulics, it can be demonstrated that the structures as above described materially improve the circulation of the oil, 50 thereby reducing tendencies to carbon formation resulting from a too restricted or retarded flow of oil.

It will be clear from the above description that I have designed a ring which will not 55 only afford sufficient cylinder contacting area without undue weakening of the ring, but will facilitate uniform, rapid and unrestricted oil circulation and drainage in an improved manner which has not been known heretofore.

Although I have shown and described only 60 two forms of piston rings embodying my invention, it will be obvious that changes may be made in the details, within the scope of the claims, without departing from the spirit 65 and scope of my invention.

What is claimed is:

1. A piston ring comprising a one-piece split annulus having centrally located intermediate its sides a single row composed of two end-to-end series of elongated slots having parallel sides and outwardly flaring end walls and severally aperturing the annulus from its inner face outwardly toward its periphery, the series being separated from each other at points that are respectively about 70 90° from the split in the annulus, by solid portions of the annulus that are intact and imperforate from their inner faces entirely to their peripheral faces, and the slots constituting each series having their outermost mutually 75 adjacent ends communicably connected by short peripheral grooves; whereby each series of slots constitutes within itself a substantially continuous oil-circulation aperturing of the annulus, while the series are severally 80 separated from and out of communication with each other and thereby severally localize the oil-circulation aperturing that they respectively provide.

2. A split piston ring containing a plurality of coplanar radial slots opening on the inner surface of the ring and separated by solid portions of the ring, certain of said radial slots adjacent the split and diametrically opposite thereto being communicably connected by short peripheral grooves of the same width as the slots and aligned therewith, said grooves being interrupted at two diametral points displaced substantially 90° from the ring joint, and said grooves forming in the outer face of the solid portions of the ring outwardly open oil-circulation ducts 90 merging into the ends of said radial slots. 95

3. A piston ring comprising a split annulus having a plurality of coplanar radial 105 openings therethrough and a series of coplanar grooves in its cylinder contacting face connecting said openings, the openings having side walls parallel to the plane faces of the ring and end walls of smooth outwardly 110 curved formation merging into the adjacent grooves.

4. A ring as set forth in claim 3, wherein the opening-connecting grooves are omitted at diametral points thereby producing cylinder contacting faces coextensive of the 115 width of the ring.

In testimony whereof I have signed my name to this specification.
